SAFETY DEVICE FOR TRANSFORMERS
WITH EXPANSION TANKS

Léon Jean Egger, Aix-les-Bains, France, assignor
to Societe Savoisiene de Constructions Elec-
triques, Aix-les-Bains, France, a French cor-
poration

Application July 18, 1949, Serial No. 105,431
In France July 20, 1948

8 Claims. (Cl. 174—11)

1

This invention relates to safety devices and is more particularly concerned with safety devices for use on electrical apparatus such as transformers.

Modern transformers provided with safety devices are generally equipped with float relays or switches of the Buchholz type or the like such as are described in the Buchholz Patent No. 1,642,398. Such float relays break the circuit or give an alarm in the event of the evolution of gases due to a more or less serious fault within the container of the transformer. Usually the float relay is located in a pipe extending from the highest point of the container and opening in the bottom or at least a few centimetres from the bottom of the oil reservoir. This arrangement has a number of disadvantages:

During normal operation, the breathing of the transformer takes place through the relay pipe. Consequently, upon heating, it is the hot, and hence oxidizable, oil from the top of the container which rises into the reservoir and becomes oxidized in contact with the air. Consequently, upon cooling, the oil at the bottom of the reservoir, which is charged with the products of oxidation flows towards the container and is deposited on the top of the windings. This deposition of impurities reduces the efficiency of the insulation.

The tripping of the circuit breaker or the alarm signal by the float relay does not occur until a considerable amount of gas is evolved. In fact, the float relay is so adjusted that it is insensitive to movements due to contraction or expansion of the oil. If an external accident results in breakage of a terminal or renting of the tank, the circuit breaker is not tripped until all the oil has drained away from the reservoir. In addition to the belated operation of the relay, the oil in the reservoir is then entirely lost and may feed any fire which breaks out at the point at which the oil escapes.

Finally in the case of a violent explosion inside the container, the transformer is immediately placed out of circuit, but the small cross section of the float relay pipe is not sufficient to allow the oil to expand and a second pipe comprising an explosion funnel must be provided.

Similar protective devices are also known which comprise, in addition to the means hereinbefore referred to a partially or completely closing non-return valve situated between the float relay and the reservoir.

In such latter cases, the float relay is sensitive to the reflux movements of the oil towards the

2

container and electrically controls the closing of the non-return valve. In this way, the draining away of the oil in the case of such reflux is partially or completely avoided, but all the other disadvantages hereinbefore referred to remain, and the operation of the non-return valve is dependent upon the correct energization of an electric circuit which may be damaged before the valve should come into operation.

10 The object of the present invention is to provide a protective device for transformers, by means of which these disadvantages can be overcome.

According to the present invention there is provided a safety device for use on electrical apparatus of a type having a part or parts thereof immersed in oil in a container, there being used with the container a reservoir containing a reserve of oil associated therewith, and a non-

15 return valve inserted in a pipe connecting the container to the reservoir, said pipe entering said container below the oil level therein and the non-return valve being adjusted so that the oil in the container can expand and contract

20 normally without affecting the non-return valve, while oil cannot flow from the reservoir to the container in large amounts, and further comprising a gas detecting device inserted in another pipe connecting the container to its reservoir, the

25 said other pipe entering into both containers above the oil levels therein, said gas detecting device being such as a float relay having a chamber which collects the gas formed in the container and will cause operation of electric contacts

30 by a float after the gas collected reaches a predetermined volume in order to ring a bell or break an electrical circuit when brought into operation. The float relay is brought into operation when the transformer is not operating properly or has been damaged as by having its terminals broken, or the oil has fermented or decomposed, by virtue of such improper operation or

35 damage, causing the formation of gas within the container A which holds the transformer. This improper operation or damage causes a marked temperature rise or the formation of electric arcs, which produces boiling or decomposition of the oil, and the formation of the mentioned gas.

40 45 50 55 Finally in the case of a violent explosion inside the container, the transformer is immediately placed out of circuit, but the small cross section of the float relay pipe is not sufficient to allow the oil to expand and a second pipe comprising an explosion funnel must be provided. This gas so formed rises in the container A from which it passes after being collected into the chamber of the float relay. The presence of bubbles of gas in this chamber of the float relay causes a decrease in the specific gravity of the oil, the float falls and actuates a circuit control

device, for example, causing the closing of an electric contact.

In order that the present invention may be better understood one embodiment thereof will now be described in greater detail with reference to the accompanying drawing.

The single figure of this drawing represents a protective device according to the invention comprising a first pipe *b* in which is provided a float relay *B*, the lower extremity of which pipe *b* is connected to the uppermost point of the container *A* of the transformer, while the upper extremity of pipe *b* opens into an oil reservoir *R* above the level *N* of the oil therein.

A second pipe *c* of larger cross section than the first pipe *b* starts from the bottom of container *A*, passes through the reservoir *R* with the inside of which it communicates through openings *d* and *e* arranged in the vicinity of the top and the bottom of the reservoir *R* respectively. The openings *e* are intended to allow the normal breathing of the transformer container, which always remains completely filled. Should the oil be driven suddenly, it also enters the reservoir through the openings *d*. In the event a still more sudden displacement of the oil should take place on account of an operation disturbance, the oil breaks a diaphragm, which is made of a very thin plate of metal of small strength, such as aluminum, and closes an explosion pipe *E*. Any over-pressure liable to distort the container is thus avoided.

The second pipe *c* comprises below the reservoir *R* an automatically closing non-return valve *C*, the said valve *C* being designed to come into operation upon return of the oil from the reservoir *R* towards the container *A*. According to the present invention, the valve *C* is so adjusted that during normal operation the movements of expansion and contraction of the oil have no effect on the valve and that it only closes for a sufficiently large flow of oil from the reservoir to the transformer container.

Finally, in order to prevent any moist air from entering, the upper part of the reservoir is adapted to communicate with the ambient air only through a third pipe *f* provided with an air dryer *F*.

With this arrangement, the transformer breathes during normal operation through the second pipe *c* only, and not through the first pipe *b*, which opens above the highest possible level of the oil in reservoir *R*. This breathing through second pipe *c* is effected by means of cold and therefore only slightly oxidizable oil which comes from the bottom of the container *A*. Should impurities become mixed with the returned oil, they will not be likely to harm the windings of the transformer in container *A* since they will be deposited on the bottom of the container.

In the event of an explosion occurring in the container *A* without any flow of oil to the outside, the float relay *B* operates the alarm or trips the circuit breaker, while the oil expands normally through the second pipe *c*, the non-return valve *C* lifting at this instant to allow the oil to pass through a cross sectional area at least equal to that of the second pipe *c*, and then immediately returning automatically to its initial position.

In the event of breakage of a terminal or renting of the container, resulting in an escape of oil with or without an explosion, the float relay *B* rapidly breaks the circuit of the transformer

by virtue of temperature rise of the oil, formation of arcs, and gas decomposition, causing evolved gas forming bubbles in the oil in the chamber of the float relay and decrease of the specific gravity of the oil in this chamber, as has been explained. At the same time, the oil in the reservoir *R* commences to flow back through the second pipe *c* and produces the automatic closing of the non-return valve *C*.

10 I claim:

1. In a protection device for an oil bath transformer combined with an oil reservoir arranged above the transformer container, a pipe connecting the top of the container with the reservoir, said pipe carrying a gas detecting device having a float located in a chamber which collects the gas formed in the container and will cause operation of electric contacts by the float after the gas collected reaches a predetermined volume, the upper extremity of the pipe ending in the reservoir above the highest possible level of the oil therein, and a second pipe starting from the lower part of the transformer container and passing through the reservoir, with 15 which it communicates with two openings disposed in the vicinity of the highest point and the lowest point of the reservoir.

2. Protection device according to claim 1, in which the second pipe is provided at the outlet 20 of the reservoir with a stopping partition whose mechanical resistance is sufficiently weak so that this partition could be broken in the case of an explosion.

3. Protection device according to claim 1, in 25 which the second pipe bears, between the reservoir and the transformer container, a non-return valve which is so constructed that it only closes for a flow of oil from the reservoir to the transformer container which is larger than the amount of oil necessary to assure the normal 30 breathing of the transformer.

4. In explosion protective apparatus for oil immersed transformers, a transformer casing having an upper oil passage at its top, and a bottom oil passage at its base, an oil reservoir mounted above said casing, a first pipe connecting said upper oil passage to the uppermost portion of said reservoir above the uppermost level of oil therein, a second pipe connected to said bottom oil passage and passing through said reservoir from bottom to top and being provided with a first orifice at the lowest point within said reservoir, and with a second orifice at the uppermost point within said reservoir, and a gas detecting device inserted in said first pipe and having a float located in a chamber which collects the gas formed in the casing and will cause operation of electric contacts by said float after the gas collected reaches a predetermined volume.

5. Apparatus, according to claim 4, said second pipe having a substantially greater cross-section than said first pipe.

6. Apparatus, according to claim 4, said gas detecting device comprising an electrical contact bar carried by said float and displaceably mounted in said chamber and displaceable by the evolution of gases through said chamber and further comprising electrical contacts mounted for engagement with said contact bar upon said displacement of said float.

7. Apparatus, according to claim 4, and a non-return valve inserted in said second pipe and remaining unactuated by normal oil expansion and contraction but being actuatable to pass explosive

surges from said casing to said reservoir and to block surges from said reservoir to said casing.

8. Apparatus, according to claim 4, and a non-return valve inserted in said second pipe and remaining unactuated by normal oil expansion and contraction but being actuatable to pass explosive surges from said casing to said reservoir and to block surges from said reservoir to said casing, and said second pipe extending to the outside of the upper part of said reservoir.
